The ornamental design for a front face of a wheel for a motor vehicle, as shown and described.

DESCRIPTION

FIG. 1 is a front view of a front face of a first embodiment of a wheel according to my novel design;

FIG. 2 is a front view of a front face of a second embodiment of a wheel according to my novel design;

FIG. 3 is a perspective view of a front face of a first embodiment of a wheel according to my novel design; and,
FIG. 4 is a perspective view of a front face of a second embodiment of a wheel according to my novel design.

The broken lines are for illustrative purposes only and form no part of the claimed design.
